MEANS FOR FORMING GLASS BOTTLES,
JARS, AND THE LIKE

Thomas Finney Pearson, Pontefract, England, assignor to Crown Cork & Seal Company, Inc., New York, N. Y., a corporation of New York

Application September 15, 1936, Serial No. 100,944
In Great Britain November 21, 1935

2 Claims. (Cl. 49—18)

The present invention relates to machines for forming glass bottles, jars and the like, and has for its object improvements in means for applying vacuum or pressure or both to the neck 5 moulds, parisons and blow moulds of said machines.

According to the present invention a plunger head is freely suspended on a displaceable guide element which lowers the plunger into an operable position within a mould or mould ring.

Preferably the suspension is by way of a resilient connection such as a spring which is mounted between the plunger and an abutment on the displaceable guide element, which abutment preferably consists of a collar integral with the guide element.

From another aspect of the present invention a hollow stem of the plunger communicating with radial passages in the plunger head has a floating 20 or resilient engagement with and extends longitudinally within a hollow stem of a diaphragm or piston, which in turn is displaceable within, and has a sealed relationship with, a chamber such as a blow head in which the plunger operates. In consequence, slight lateral displacement 25 is possible of the plunger head relatively to a neck or other mould in which the plunger operates, in order to establish alignment therewith during working, said alignment being effected automatically without the necessity of using glands or the like for preventing leakage through the plunger mounting during the application of pressure or vacuum.

The invention is more particularly described with reference to the accompanying drawing in 30 which:

Figure 1 is a longitudinal vertical section through a blow head and its associated plunger.

Figure 2 is a section on the line 2—2 of Figure 1.

In the drawing a hollow blow head 10 is connected by a neck ring holder 11, which is formed of two semi-circular pivotal half ring elements, to a neck ring adaptor 12, adapted to support a neck ring 13, the two halves of the neck ring holder being angularly displaced about a pivot 14 to open the half portions and permit of separation of the neck ring and its adaptor from the blow head.

A diaphragm 15, having a piston fit within the blow head 10 and provided with the usual packing rings on its periphery has a hollow stem 16 which terminates in a cap 17 having an internal shoulder 18. A plunger 19 having a hollow stem 20 is provided with radial passages 21, in connection with the bore of the hollow stem 20, the latter having an enlarged end 21, which is complemen-

tary to the shoulder 18 of the cap 17 on the free end of the stem 16 of the diaphragm 15, so that the enlargement 21' of the upper end of the stem 20 rests freely on the shoulder 18, that is to say the plunger 19 is freely suspended from the diaphragm. A spring 22 is located between the shoulder 18 of the diaphragm unit and the upper radial face of the plunger so that the plunger is both freely and resiliently suspended from the diaphragm. In addition, a second 10 spring 23 is mounted between the cap 17 and the upper end wall of the blow head so that the diaphragm 15 when displaced longitudinally within the blow head 10 moves against the action of the spring. It will be seen that when the pressure or vacuum is applied through the open end 24 thence through the bore of the stem 20 and the radial passages 21 of the plunger 19 to compact a charge of glass held by the neck ring or to partially blow or wholly blow said charge into 20 a hollow article of glassware, the only place which leakage may take place is between the complementary elements 21', 18 which is wholly immaterial in as far as successful operation of the apparatus is concerned. By this means a 25 free suspension of the plunger within the blow head structure is obtained to permit the plunger to center itself in the neck ring when it is displaced into the latter prior to applying a vacuum on, or blowing the charge held by the neck ring. 30

I declare that what I claim is:

1. In a glass forming apparatus, a plunger adapted to be moved into forming relationship with a mold, a hollow stem secured to the plunger, a movable guide element having a hollow stem 35 surrounding the first mentioned stem, the respective diameters of said stems being such as to permit slight relative lateral movement, an enlarged head on the first mentioned stem and an internal shoulder on the second mentioned stem 40 engaging and supporting the head.

2. In a glass forming apparatus, a plunger adapted to be moved into forming relationship with a mold, a hollow stem secured to the plunger, a movable guide element having a hollow stem 45 surrounding the first mentioned stem, the respective diameters of said stems being such as to permit slight relative lateral movement, an enlarged head on the first mentioned stem, an internal shoulder on the second mentioned stem 50 engaging and supporting the head and resilient means acting between the shoulder and the plunger tending to effect relative movement therebetween. 55

THOMAS FINNEY PEARSON.
